UNITED STATES PATENT OFFICE

139,413

DESIGN FOR A COMBINED BILLFOLD, PASS HOLDER, AND KEY HOLDER

Samuel J. Smallman, New York, N. Y.

Application September 8, 1944, Serial No. 115,226

Term of patent 14 years

(Cl. D87—3)

To all whom it may concern:

Be it known that I, Samuel J. Smallman, a citizen of the United States of America, residing in city of New York, county of New York, and State of New York, have invented a new, original, and ornamental Design for a Combined Billfold, Pass Holder, and Key Holder, of which the following is a specification, reference being had to the accompanying drawing, forming part thereof.

Fig. 1 is a front view of a combined billfold, pass holder and key holder showing my new design with the pass holder which is detachable in closed position.

Fig. 2 is a fragmentary view of the right side of the article as shown in Fig. 1 with the pass holder in open position.

Fig. 3 is a fragmentary view of the right side of the article as shown in Fig. 2 with the pass holder removed.

The back of the article is substantially plain.
I claim:

The ornamental design for a combined billfold, pass holder, and key holder, substantially as shown and described.

SAMUEL J. SMALLMAN.
